CLAIM

The ornamental design for a handheld cleaner, as shown and described.

DESCRIPTION

FIG. 1 is a rear-top-left side perspective view of a handheld cleaner showing our new design;

FIG. 2 is a front-bottom-right side perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines shown in the drawings are included for the purpose of illustrating portions of the handheld cleaner that form no part of the claimed design.

1 Claim, 8 Drawing Sheets
